FLEXIBLE RAIL JOINT

Bancroft G. Braine, Montclair, N. J., assignor to
Poor & Company, New York, N. Y., a corpora-
tion of Delaware

Application October 28, 1937, Serial No. 171,573

1 Claim. (Cl. 238—243)

This invention relates to an improvement in the flexible type of rail joints providing practical and effective construction to support the extreme end portions of the rails and to permit the natural wave motions of the rails to pass substantially uninterrupted through the joint despite the loading engagement of the head of the bar with the rails throughout the length of the joint.

The invention possesses special utility and practical importance in connection with rail joints of the type wherein the head of the bar has a relatively narrow line of contact with the rails, this being exemplified more particularly in the headfree type of rail joint wherein the splice bar 15 has its loading engagement at its upper inner corner with the head fillets of the rails, and while the invention is particularly and preferably applicable to the headfree type of rail joint it also is applicable to a type of rail joint wherein the head of the splice bar may have a relatively narrow or line contact with the underside of the rail head and which ultimately would take a headfree seating in the rail head fillets.

In carrying forward the invention it is 25 recognized very undesirable to have the joint so stiff and rigid as to disadvantageously preclude the possibility of the natural wave motion of the rails passing freely through the joint. Accordingly, one important object of the present invention 30 is to provide a rail joint wherein the splice bar has uninterrupted loading engagement at its upper, inner corner with the head fillets of the rails throughout the length of the joint, and which, at the same time embodies provision to 35 permit the natural wave motion of the rails to pass substantially uninterrupted through the joint.

In a rail joint, an accurate initial fit between the splice bar and the rails is very desirable, as 40 otherwise tightening of the joint bolts may result in the setting up of damaging stresses and strains in the joint. Since, however, rails and splice bars are essentially rolled products, and since there are unavoidable variations in the dimensions of 45 rolled products, aggravated by unavoidable surface irregularities, a perfect initial fit between the splice bar and the rails of a rail joint is practically impossible of attainment. Moreover, especially in a headfree rail joint, any imperfection in fit between the splice bar and the rails, either at the head or the base of the joint and particularly at the head of the joint, is very undesirable due to the relatively narrow maximum width of the contacting head surfaces of the rails 55 and the bar and because of the transverse curva-

ture of said surfaces. Accordingly, another important object of the present invention is to provide a headfree rail joint wherein a condition approximating a perfect initial fit, and, in any event, a fairly accurate fit, between the splice bar and the rails is obtained upon tightening of the joint bolts, and wherein this condition is improved by the action of the joint in service, without the setting up of damaging stresses or strains in the joint by the joint bolts or by traffic passing over 10 the joint.

Another important object of the invention is to provide a headfree rail joint wherein there is continuous loading engagement, throughout the length of the joint, between the head of the splice 15 bar and the rails, and wherein the areas of base contact between the splice bar and the rails are, respectively, at the middle and the ends of the joint, with easements or clearances therebetween, thereby to most effectively transmit the wave motion 20 of the rails through the joint and to most effectively transmit the load to the cross ties or other supports usually located under the ends of the joint.

With the foregoing and other objects in view, 25 which will become more fully apparent as the nature of the invention is better understood, the same consists in the novel splice bar construction, and in the novel combination of features in a headfree rail joint, as will be hereinafter more 30 fully described, illustrated in the accompanying drawings and defined in the appended claims.

In the accompanying drawings, wherein like characters of reference denote corresponding parts in the different views:

Figure 1 is a side elevation of a headfree rail joint embodying the features of the invention;

Figures 2, 3 and 4 are transverse sections on the lines 2—2, 3—3 and 4—4, respectively, of Fig. 1.

Figure 5 is a side elevation of a modified form 40 of rail joint wherein the head of the splice bar takes an initial relatively narrow loading engagement at the underside of the rail head.

Figures 6, 7 and 8 are cross-sectional views respectively on the lines 6—6, 7—7 and 8—8 of 45 Fig. 5.

Referring to the drawings in detail, R, R designate the meeting end portions of a pair of rails, each including, as usual, a head 10, a web 11 and a base 12; B designates, generally, a splice bar constructed in accordance with the invention and including, as usual a head 13, a web 14 and a foot or base 15, and C designates joint bolts for drawing the splice bar into engagement with the rails.

The splice bar B may be of any desired sectional 55

shape and, in accordance with the invention, is preferably formed at its top to have clearance from the under sides of the rail heads, as indicated at 16, and at its upper, inner corner to take loading engagement with the head fillets 17 of the rails, its said upper, inner corner being rounded, as indicated at 18, similarly to the rounding of the fillets 17, to fit said fillets.

At its base the bar B has flat surface engagement medially, as indicated at 19, and at its ends, as indicated at 20, 20, with the upper faces of the bases of the rails, but between its middle and its ends said bar has clearances at its base from the upper faces of the bases of the rails as indicated at 21, 21, said clearances being provided by forming easements or recesses in the base of the bar in any suitable manner.

The engagements 19 and 20, 20 may be of any suitable length, but preferably the medial engagement 19 approximates in length the length of the zone of maximum wear medially of the joint at the base thereof and extends continuously from end to end of said zone. Said engagement, in conjunction with the continuous head engagement of the bar with the rails, and in conjunction with the base engagements 20, 20 at the ends of the joint, thus is very effective in supporting the extreme end portions of the rails and transmitting the natural wave motion of the rails through the joint. On the other hand, due to the clearances 21, 21 and the consequent flexibility of the joint, the natural wave motion of the rails is permitted to pass substantially uninterruptedly through the joint despite the loading engagement of the head of the bar with the rails throughout the length of the joint. Moreover, due to the clearances 21, 21 and the consequent flexibility of the splice bar, the rounded, upper, inner corner of the bar is permitted initially to seat itself, throughout the length of the joint, with the head fillets of the rails upon normal tightening of the joint bolts and despite any irregularities in the surfaces of said corner and the rail head fillets and without the imposition by the joint bolts of any undue stresses or strains in the joint. Furthermore, the clearances 21, 21 and the consequent flexibility of the splice bar permits relative vertical movement between the head of the splice bar and the rail heads at locations above said clearances when loads are imposed on the joint, thereby contributing to the maintenance of an accurate clinging fit of the splice bar with the rails. Still further, the relatively long medial base engagement 19 of the splice bar with the bases of the rails transmits loads imposed on the extreme ends of the rail heads to the base of the joint at points spaced well back from the rail ends and toward the end base engagements 20, 20 through which the load is most advantageously transmitted to the usual supports underlying the ends of the joint.

While the invention as described in connection with Figures 1, 2, 3 and 4 is preferably embodied in a headfree type of rail joint, nevertheless, a practical modification thereof is exemplified in Figures 5, 6, 7 and 8 of the drawings. In this modification all of the structural and useful fea-

tures are preserved and utilized in connection with a very practical form of splice bar whose head 13 is provided with a top surface convexly curved transversely or equivalently formed, to provide a relatively narrow contact surface 22 in contact with the flat underside of the rail head. This narrow contact surface 22 on the head of the bar provides in effect a continuous line contact with the flat underside of the rail head and which line contact constitutes the sole contact of the head of the bar with the rail. The practical purpose of this so-called line contact 22 for the head of the bar with the underside of the rail head is to provide for initial and subsequent continuous contact of the head of the bar throughout its length with the rail head and while the initial contact of the head of the splice bar with the rail is practically a line contact as shown in Figure 6 of the drawings, such contact gradually widens into a surface contact as shown at 22^a in Figure 7 which surface contact progressively increases in width as indicated at 22^b in Figure 8 as wear takes place partly on the underside of the rail head and partly on the head of the bar until the head of the bar in effect takes a headfree seating in the rail head fillets, as shown in Figure 8. It will therefore be observed that this modification of the invention shown in Figures 5 to 8 inclusive provides a novel and useful combination of features which include all of those features which give merit to the primary form of the invention shown in Figures 1 to 4 inclusive of the drawings.

Without further description it is thought that the features and advantages of the invention will be readily apparent to those skilled in the art, and it will of course be understood that changes in the form, proportion and minor details of construction may be resorted to, without departing from the spirit of the invention and scope of the appended claim.

I claim:

A flexing rail joint structure comprising in combination, the rails, the splice bar and joint bolts for adjustably holding the bar into engagement with the rails, the said splice bar having at its head an upper rounded contact portion for engagement with the rails and extending uninterruptedly the full length of the bar for continuous loading engagement with the rails throughout the length of the joint, the foot of the said splice bar having a full width bearing portion for engagement with the rail flanges at the center of the joint throughout the zone of maximum wear and full width bearing portions for engagement with the rail flanges at the ends of the joint, and the said foot of the bar also being provided between the center and each end of the joint with a recess extending entirely across the underside of the foot of the bar and providing complete clearance from the rail flange at this location thereby permitting relative vertical movement between the rail contacting head portion of the splice bar above the recess whereby the splice bar is held to a close fit with the rails while permitting rail wave motion to pass through the joint.

BANCROFT G. BRAINE.
